UNITED STATES PATENT OFFICE.

ARCHIBALD B. JONES, OF SAN FRANCISCO, CALIFORNIA.

THERMOSTATIC FIRE-SIGNAL.

1,213,654.

Specification of Letters Patent. Patented Jan. 23, 1917.

Application filed March 30, 1914. Serial No. 828,375.

To all whom it may concern:

Be it known that I, ARCHIBALD B. JONES, a citizen of the United States, residing at San Francisco, in the county of San Francisco and State of California, have invented certain new and useful Improvements in Thermostatic Fire-Signals; and I do hereby declare the following to be a full, clear, and exact description of the invention, such as

10 will enable others skilled in the art to which it appertains to make and use the same.

My invention relates to improvements in thermostatic fire signals and resides in the provision of a device which will operate to 15 signal automatically by the heat given forth from a starting conflagration.

An important object of my invention is to provide a thermostatic signal of the character described which may be regulated to 20 operate at different temperatures.

Great loss of life has been brought about through fires in hotels and on ship board, and my invention aims to provide means for 25 warning the occupants or passengers as the case may be of a starting conflagration, thus enabling the person or persons when warned to extinguish the fire or to give the proper alarm.

Another important object of my invention 30 is to provide a signaling means of the character described which may be arranged in great numbers at different points throughout the ship, house or building to which it is applied, thus insuring detection of a 35 starting fire at any point in the ship or building.

Another important object of my invention 40 is to provide signaling means of the character described which is simple as to construction, reliable and efficient in operation, cheap to manufacture and install and which is entirely automatic in its operation.

The above and additional objects are accomplished by such means as are illustrated 45 in the accompanying drawings, described in the following specification and then more particularly pointed out in the claim which is appended hereto and forms a part of this application.

50 With reference to the drawings, wherein I have illustrated the preferred embodiment of my invention as it is reduced to practice, and throughout the several views of which similar reference numerals designate corresponding parts: Figure 1 is a front elevation 55 of my device showing the electrical circuit

therefor in diagram. Fig. 2 is a transverse sectional view taken through the means for adjustably supporting the adjustable contact rod or electrode, and Fig. 3 is a fragmentary vertical sectional view of the means for hermetically sealing the opening through which the adjustable contact rod or electrode is inserted into the mercury tube of the thermometer.

65 Referring to the drawings, the numeral 1 designates as an entirety a thermometer consisting of a base or wall plate 2 which is provided with the usual characters and graduations designated 3 as an entirety. 70 The usual glass mercury container 4 having mercury 5 therein is disposed in the usual manner upon the board 2. The upper end of the tube 4 is enlarged to provide a shoulder 6 and cup 7. A contact rod or electrode 8 is mounted within the tube 4 and is extended through the cup 7 formed as described. This contact rod or electrode 8 is adjustable through a sleeve or collar 9 carried upon one end of an angular supporting 75 arm 10. The supporting arm 10 is secured by suitable fastening means 11 to the upper portion of the wall board 2. A set screw 12 cooperating with the collar or sleeve 9 provides for the securing of the rod or electrode 8 in adjusted position as will be readily seen with reference to Figs. 1 and 2 in the drawings.

80 As a means for hermetically sealing the opening in the tube 4 and into which the rod 8 is extended I provide a flexible washer or collar 13 that is provided with a small central aperture of sufficient size to receive the rod 8 and designed to rest upon the shoulder 6 formed as described. The outer face 85 of this washer 13 is disposed in inwardly spaced relation to the outer edge of a cup 7 to provide a space into which is poured paraffin or some other suitable sealing medium. The paraffin is poured as described after the desired adjustment of the rod 8 is had, thus insuring the proper sealing of the tube 4.

80 An electrical circuit is employed in connection with the thermometer 1 and consists of a battery or other suitable source of current 14 having one conducting wire 15 leading to a suitable annunciator 16 and from thence by means of a conductor 17 to a binding post 18 formed on the outer end 110 of the contact rod or electrode 8. A conducting length 19 comprising the other side

of the circuit connects the battery 14 with a binding post 20 carried on the lower portion of the wall board 2 of the thermometer 1. A suitable electrode wire or rod 21 is 5 connected at one terminal with the binding post 20 and at its other terminal is disposed within the lower ball portion 22 of the tube 4 for the mercury 5. This electrode 21 is grounded in the mercury 5 and the opening 10 through the ball portion 22 of the tube 4 through which the electrode 21 extends may be sealed by some suitable sealing medium such as paraffin or the like.

If desired the electrode 21 may be molded 15 in the ball portion 22 of the tube 4.

It will be readily seen that the current through the medium of the wire 19 and electrode 21 is grounded with relation to the mercury 5. It will be readily seen that when 20 the mercury 5 in the tube 4 of the thermometer 1 rises to the point at which the lower end of the electrode 8 is disposed, the circuit will be closed and the annunciator operated.

It will be noted with reference to the foregoing description and accompanying drawings that the annunciator may be arranged to operate according to the heat temperature desired. This action is had by the adjustment permitted the electrode 8. The 25 electrode 8 may be arranged so that its inner operative terminal is disposed adjacent to certain points of the temperature scale, for instance, if arranged to operate at 60 degrees the electrode terminal is disposed opposite to the 60 degree graduation and when the mercury rises to this point the circuit 30 is closed and the operation of the annunciator is brought about.

It will be noted with reference to the foregoing description and accompanying drawings that my device may be used with good results in connection with battleships and forts or other places where great quantities of explosives are stored. The thermometer 40 1 with the coöperating parts may be placed adjacent to the magazines for the explosives while the annunciator may be arranged in the captain's or officers' quarters. Thus when a dangerous temperature is had adjacent to the magazine the officers or captain 45 will be notified.

It will thus be seen that my device will be of great use in connection with powder magazines and the like. My device is particularly desirable for use in the connection 50 before described for reason of the adjustment permitted the electrode whereby the

device will operate at different heat temperatures. This point is considered one of the most essential of my invention.

It will be readily noted with reference to the foregoing description and accompanying drawings that I have provided a simple and inexpensive signaling device which will operate in a reliable and expeditious manner and which is cheap to manufacture and install.

My improved device may be readily used in connection with return call annunciator systems of different characters.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

What is claimed is:—

A thermostatic signaling device including a graduated base plate provided at one end with a binding post, a mercury tube supported on the base plate and provided at its upper end with an integral cup, an electrode embedded in the mercury at one end of the tube and connected with the said binding post, a transversely disposed supporting arm located beyond the other end of the tube and secured at one end to the base plate and provided adjacent to such attached end with an outward bend and having its other end free and provided with a collar arranged in alignment with the said tube, a clamping screw carried by the collar, a contact rod passing through the collar and adjustably clamped by the said screw and extending through the cup into the said tube, said rod being provided at its outer end with a binding post, a sleeve fitted in and bearing against the bottom of the said cup and pierced by the said rod, and a plastic seal contained within the cup and supported by the said sleeve.

In testimony whereof I affix my signature in presence of two witnesses.

ARCHIBALD B. JONES.
